UNITED STATES PATENT OFFICE.

CHARLES LEWIS PASSMORE, OF CLINTON, IOWA.

SHOE-STRETCHER.

No. 921,152.

Specification of Letters Patent.

Patented May 11, 1909.

Application filed May 11, 1908. Serial No. 432,097.

To all whom it may concern:

Be it known that I, CHARLES LEWIS PASSMORE, a citizen of the United States, residing at Clinton, in the county of Clinton and 5 State of Iowa, have invented a new and useful Shoe-Stretcher, of which the following is a specification.

The object of my invention is to provide a shoe stretcher of simple, durable and inexpensive construction, designed to be permanently secured to a stationary support in such position that it is readily and easily accessible for use, and also so arranged that it may be adjusted for stretching shoes of 10 different sizes and shapes, and for applying pressure to shoes at different points, as required in stretching shoes to comfortably fit the wearer's feet.

My invention consists in the construction, 20 arrangement and combination of the various parts of the device, whereby the objects contemplated are attained, as hereinafter more fully set forth, pointed out in my claims and illustrated in the accompanying drawings, 25 in which—

Figure 1 shows an edge view of the complete device embodying my invention. Fig. 2 shows a side elevation of same. The dotted lines therein indicate a shoe in position on 30 the stretcher and also show the adjusted position of the movable stretching member and lever. Fig. 3 shows a side elevation of one of the detachable knobs on the stretching members, and Fig. 4 shows an end view of 35 same.

Referring to the accompanying drawings, I have used the reference numeral 10 to indicate the body of the device, which is provided with legs 11, the lower ends of which 40 are beveled or inclined in such a manner as to support the body at an angle of about 45 degrees relative to a horizontal table or other support on which the legs are fixed. The body is also provided with a lateral 45 curve near its central portion, so arranged that a shoe may be placed upon the body portion in the position shown by dotted lines in Fig. 2, and the upper portion of the body may then rest inside of the shoe. This 50 obviously would not be possible if the body portion were not provided with the lateral curve.

At the upper end of the body portion 10 is a socket in which a stationary arm 12 is 55 detachably supported. This arm extends straight upwardly in line with the body por-

tion 10, and its upper end is tapered. Pivotally mounted in the upper end of the body portion 10 is an arm 13 similar to the arm 12, and having a lever 14 connected with it, and extended substantially horizontal. When the upper end of said lever is moved downwardly, the arm 13 is moved away from the arm 12, and when the lever is moved upwardly, the arm 13 is moved toward the arm 12. 60

On the upper end of each of the arms 12 and 13 is a knob 15 designed for engagement with the interior of a shoe, for the purpose of stretching the shoe at the points where 70 said knob engages. Each of these knobs is provided on one side with a rounded outer end portion at 16, that does not project beyond the side of the knob, and on the opposite side of the knob is a rounded projection 75 17. The knob is provided with a tapered opening 18 designed to detachably fit on the tapered end of one of the arms 12.

In practical use, the device is preferably placed upon a horizontal bench or table, and 80 by having the arms 12 and 13 inclined at the angle shown, an operator may very conveniently and easily place a shoe in position with the arms 12 and 13 inside of the shoe, and the lever 14 projecting out through the 85 side of the shoe, then the shoe is placed in position so that the knobs 15 will engage the shoe at the point where it is to be stretched, then the operator presses downwardly upon the outer end of the lever 14, thus spreading 90 the knobs 15 and forcing them to stretch the shoe at the points where they engage.

By having a stationary body portion attached to a base, it is obvious that the stretcher is always held in position where it 95 would be convenient for use by the operator, and furthermore, a comparatively long lever may be used, which may be conveniently and easily actuated by the operator's one hand, for the purpose of applying a considerable pressure to the stretching members. In devices of this class, that are not provided with stationary base portions, it is obvious that the pressure that may be applied by an operator is comparatively limited, and that both hands must be used in order to apply this pressure. In my device, one hand may be used to hold and support the shoe, and the other to operate the single lever. 100

By having the knobs formed with rounded projections on one side, it is obvious that 110

when said rounded projections are made to engage the shoe, the shoe may be stretched to a great extent at the point where said rounded projection engages, hence, if the 5 wearer of the shoe has a corn or bunion, the shoe may be stretched at the point where said corn or bunion engages it, and at no other points adjacent thereto, or if it is desired to stretch the shoe through a greater 10 portion of its length, then the comparatively flat sides of the knob are made to engage the shoe. Furthermore, by having said knobs detachable, others may be substituted in place of them, which others may be of any 15 desired size or shape to suit the requirements.

I claim as my invention.

1. In a device of the class described, the 20 combination of a body portion designed to be permanently connected with a base, a stationary arm connected with the body portion, and a combined arm and lever pivoted to the body portion, said arm being capable of movement to position substantially parallel 25 with the stationary arm, and also to position at an acute angle relative thereto, and said lever being extended in a position substantially at right angles to the arm, for the purpose stated.

2. In a device of the class described, the 30 combination of a support designed to be permanently secured to a base and having a curved central portion so shaped that the top of the body is out of alinement with the 35 lower end of the support, a stationary arm connected with the base and having a knob at its upper end and a combined arm and lever pivoted to the base, said arm having a knob at its upper end and said lever being extended at substantially right angles 40 to the arm, for the purposes stated.

3. In a device of the class described, the 45 combination of a base, a body portion fixed to the base and extended at an angle of about 45 degrees relative thereto, said body portion being provided with a curved central portion so arranged that the upper part of the body is out of alinement with the

lower part, a stationary arm connected with the support, a rounded knob at the top 50 thereof, and a combined arm and lever fulcrumed to the support, said arm having a rounded knob thereon and said lever being extended substantially at right angles to the 55 arm, for the purposes stated.

4. An improved shoe stretcher comprising a standard, a stationary arm fixed to the standard and having an angular upper end, a lever fulcrumed to the standard and having an arm thereon arranged at the side of 60 the aforesaid arm and having an angular upper end, and a knob for each arm comprising a body portion having an angular opening therein to receive the angular end of the arm, the upper end portion of each 65 knob being rounded and being provided on one side with a rounded lateral projection, said parts being so arranged that either or both knobs may be placed in position on the arms with the rounded projections extended inwardly, and the smooth rounded portions of the knobs in position to engage the sides of a shoe, the said knobs being reversible so that one or both rounded projections will extend outwardly and engage the interior 70 of a shoe.

5. In a shoe stretcher, the combination of a standard having a socket at its upper end, an arm detachably mounted in said socket, a lever pivoted adjacent to the socket and 80 having an integral arm thereon, both of said arms having tapered angular upper ends, and a knob on the upper end of each arm, each knob comprising a body portion having tapered angular openings therein 85 designed to receive the upper end of the arm, and each also having a rounded upper end provided on one side with a lateral rounded extension arranged and combined substantially in the manner set forth, and 90 for the purposes stated.

Des Moines, Ia., March 18, 1908.
